UNITED STATES PATENT OFFICE.

HARRY D. WILLIAMS, OF PITTSBURGH, PENNSYLVANIA.

INTERNAL-COMBUSTION ENGINE.

Application filed October 5, 1920. Serial No. 414,775.

To all whom it may concern:

Be it known that I, HARRY D. WILLIAMS, a citizen of the United States, and a resident of Pittsburgh, in the county of Allegheny and State of Pennsylvania, have invented a new and useful Improvement in Internal-Combustion Engines, of which the following is a specification.

This invention relates to internal combustion engines. More particularly it relates to rotary engines, and more specifically yet it relates to rotary engines in which not only the cylinders revolve, but also a member which is rotated thereby.

The objects of the invention are to provide a rotary internal combustion engine in which a plurality of cylinders are so mounted that they drive a rotary member to which their pistons are connected, the cylinder member following the driven member with the same speed of rotation. The cylinders are tangentially disposed with relation to the central shaft carrying them. The invention also includes special ignition, valve and lubricating means for internal combustion engines of this class.

In the accompanying drawings a simplified engine construction embodying the general principles which constitute this invention is illustrated. Certain details, such as the lubrication system, the ignition system, and the valves are shown in a form that is largely diagrammatic, it being intended to illustrate an operative engine, but it being understood that many refinements and details are omitted, for the purpose of presenting the essentials of the invention in the simplest possible form.

Referring to the drawings, Fig. 1 is an end elevation, partial section, and in general a diagrammatic view of the engine cylinders, and the spider, or fly wheel driven thereby; Fig. 2 is a partial vertical section and elevation at right angles to the view shown in Fig. 1, with certain details omitted. This view shows the lubrication system for the engine; Fig. 3 is a vertical section through the gear box, taken on the line III—III, of Fig. 2; Fig. 4 is a central vertical section through the cylinder block, showing the arrangement of valves for the cylinders; Fig. 5 is a vertical section through a special cam arrangement for operating the valves; this view being a section on the line V—V of Fig. 6; Fig. 5^a shows the upper part of the cam arrangement of Fig. 5, the

guides being in a different position; Fig. 6 is a partial side elevation showing the cam member; Fig. 7 is a partial end view of the cylinder block showing diagrammatically part of the ignition wiring; Fig. 8 is a partial side elevation at right angles to that of Fig. 7, showing diagrammatically the wiring of the ignition system; and Fig. 9 is a diagrammatic view of the timer device for the ignition system.

Heretofore rotary explosive engines have been made having a plurality of cylinders, which when the engine is operated rotate about a shaft to which the pistons of the cylinders are eccentrically connected by a crank, the rotation of the cylinders being produced by the pistons pushing against the stationary crank.

Fig. 1 shows the necessary elements of the present invention, without details. A plurality of cylinders, as for example cylinders 1, 2, 3, illustrated, are shown cast en bloc, and are disposed on the three sides of an equilateral triangle, the middle point of the block being keyed upon a shaft 400. It will be understood that Fig. 1 is diagrammatic merely, and that the valves and ports and intake manifold which are enclosed inside the triangular part of the cylinder block are not shown, for the purpose of clearness in illustrating the essential features of the invention.

The cylinders, 1, 2, 3, enclose the ordinary pistons 4, having annular oil grooves 5 and hollow connecting pins 6, these pins being connected by ordinary piston rods 7, to the circular rim of the fly wheel, or spider 8. The fly wheel has three or more spokes 9 and a hub 9^a, and is keyed at its central point on a shaft 10. The cylinders are air-cooled and therefore carry exterior fins 12. The shafts 10 and 400, which are parallel but eccentric are carried in stationary bearings, and are extended laterally, the extended ends being shown in Fig. 2 of a smaller diameter than the main parts of the shafts, and overlap in a gear box 15, more fully described below, and illustrated in Fig. 3. Keyed on the end of shaft 10 is a gear wheel 16, and on the end of shaft 400 is a gear wheel 17, while an intermediate gear 18 is keyed upon a gear shaft 19, as illustrated in Fig. 3. The gears 16, 17, and 18 are of the same size, and the gears 17 and 16 mesh with the gear 18, so that the shafts 10 and 400 are positively connected, so that

they can only turn in the same direction, and at the same speed.

Returning to Fig. 1, since the cylinder block is mounted on and keyed to the shaft 400 and the fly wheel 8 is mounted on and keyed to the shaft 10 it is obvious that when one is rotated about the axis of its shaft the other is also made to rotate about the axis of its respective shaft. And since they rotate synchronously, it is obvious that when the cylinder 1 has been turned one-third of a revolution to the position of cylinder 2 and two-thirds of a revolution to the position of cylinder 3, the pin (20^a) will also have been turned one-third and two-thirds of a revolution to the positions 20^b and 20^c respectively. The piston 4^a in cylinder 1 would assume the positions illustrated by pistons 4^b and 4^c in cylinders 2 and 3. Thus when the cylinder block and flywheel are rotated a reciprocating movement of the pistons within the cylinders is produced, the piston being furthest out in the cylinder when the cylinder is exactly opposite the position of cylinder 1, Fig. 1. Vice versa when a pressure, as of exploded gases in the cylinder, is exerted on the piston, driving it outward in the cylinder the whole mechanism is made to rotate.

30 It will be understood that I may use more than three cylinders, either by casting a greater number en bloc, or as separate units to form a block, or by duplicating the number of these blocks upon the same shaft.

35 Or I could employ other means for making the cylinder block revolve synchronously with the fly wheel as for instance, a separate shaft below with spur gears and chain drive.

40 The above description is the essential part of my invention. That is, the provision of a rotary engine comprising a rotary cylinder block, either cast en bloc or with separate cylinders, a rotary driven member connecting to the pistons in the engine cylinders, the rotary driven member being keyed upon a shaft which is connected through an intermediate gear to the shaft upon which the cylinder block is keyed, so that the cylinder blocks constantly follow the driven member, the shafts being parallel but eccentric.

50 Having thus described the essential parts of my invention I will now proceed to describe certain details, necessary to make an operative device embodying the general principles above set forth.

An arrangement of valves which may be used for controlling the fuel supply of the engine is illustrated in Fig. 4, and in Figs. 5 and 6, the means for controlling these valves is shown. The intake is through the bore 31 in shaft 400 from some suitable type of ordinary carburetor.

55 In Fig. 4 the cylinders are in the same position as shown in Fig. 1, with the valves

and connections in proper working relation to the engine when it is in the position illustrated. Cylinder 1 is in practically the position for explosion. A charge of fuel has been compressed in that cylinder, and its combustion drives the piston 4^a throughout the length of the cylinder, somewhat further out than the position illustrated by the piston 4^b, in cylinder 2, of this figure. Thereafter as the cylinder 1 passes on around to 70 the position occupied by the cylinder 3 of this figure, the piston will have commenced its return stroke, or scavenging stroke, driving out the spent gases. When it gets around to its original position illustrated 75 by the cylinder 1, in this figure, it will have driven out the spent gases, and the piston will then draw in a fresh charge of fuel, this intake being mostly completed when the piston reaches the position occupied by cylinder 2, which will then have started to compress when the piston passes to the position here occupied by cylinder 3, and when reaching the original position occupied by cylinder 1 in this figure, the charge will have 80 been compressed, and will be ready for another explosion. Thereupon the cycle above stated will be repeated. As is obvious from this description the arrangement shown 85 illustrates a four-cycle engine in which each cylinder explodes at every other revolution 90 of the cylinder block about its axis.

95 Each cylinder operates in a cycle similar to that above described for cylinder 1 and fires when in a position corresponding to top dead center in an ordinary crank-shaft motor, and each cylinder explodes approximately as it reaches this position on every other revolution.

100 Each cylinder has a single combined inlet and exhaust port 25. These passages lead to cylindrical valve chambers 26, which have ports 27 leading to exhaust passages 28, which open out to the atmosphere. The chambers 26 also have ports 29, which open 105 into a fuel intake manifold 30, which surrounds the hollow shaft 400, the manifold chamber 30 being connected to the central bore 31 of the shaft 4 by a plurality of ports 32, all as clearly illustrated in Fig. 4. In the 110 description just above referred to the elements 25, 26, 27, 28, and 29 are in each instance given suffixes "a," "b," and "c," 115 respectively, denoting the cylinders 1, 2, and 3, and this system is followed throughout in 120 referring to parts which are common to the three cylinders.

125 The cylindrical chambers 26 are controlled by rotary valves 35 which are adapted to oscillate in the arrangement shown in Fig. 4, so as to close the ports 25 during the power and compression strokes and open the intake and exhaust ports at the proper time. The arrangement shown in 130 Fig. 4 in connection with cylinder 1 is for a

power stroke. After the power stroke, when the cylinder which has just exploded has passed to the position illustrated by cylinder 3, the valve 35^a will have been turned to the position shown at the right of Fig. 4, in connection with cylinder 3. That is, valve 35^a will have been turned to the position illustrated by the valve 35^c, thus opening the passage 25^c, through the valve chamber 26^c, 10 port 27^c, and out to the exhaust 28^a, so that the gases may be exhausted by the scavenging or return stroke of the piston.

Then when the cylinder has passed through the scavenging stroke, as illustrated 15 at the upper right of the figure, and partially completed its intake stroke, it will have come to the position illustrated at the bottom of the figure by cylinder marked 2. In this position the valve 35^b will have turned to the position illustrated at the lower lefthand corner, freeing the ports 25^b and 29^b, so that a charge of fuel is drawn from the manifold 30 into the explosive chamber. Before the next stroke the valve 25 35^b will have turned to the position illustrated by 35^a at the upper left of the figure, closing the port 25^b, so that on the next stroke the explosive charge will be compressed, thus bringing the cylinder back to the position shown by cylinder 1, in the drawings, and ready for another explosion. This arrangement of valves and its operation will be apparent to those familiar with the art.

35 The rotation of the valves 35 is effected through a cam arrangement illustrated in Figs. 5 and 6. This comprises a cam plate 40 mounted on the shaft 400, but not keyed on that shaft. Each of the valves 35 has a suitable extension 45, the outer end of which is of non-circular form. In Fig. 6 the general arrangement of the cam member 40 and the extended valve stems 45 is illustrated. However, for the purpose of clearness only one of the valve stems is shown, but it will be understood that the arrangement is similar for each cylinder. Mounted on the extension 45 of each valve is a crank arm 46, which carries at its end an outwardly extending pin 47, upon which is mounted an idle roller 48. These rollers 48 extend into grooves on the inner face of the cam member 40.

55 Referring to Fig. 5, which shows in section a view of the inner face of the cam member 40, it will be observed that there is a series of four cam grooves, marked 50, 51, 52, and 53, respectively, the groove 50 being the nearest to the center. The inner cam groove 50 has a transition portion 54, which leads it into the next cam groove 52.

60 The cam member 40 being held stationary on the shaft 4 by lugs which straddle a rib of the stationary bearing, it is obvious that when the cylinder block and the valves car-

ried thereby revolve about the axis of the shaft 400 that the valve rollers 48 which extend into the grooves of the cam member 40, will, in following the path of travel through said groove, partially rotate the 70 valve shaft 45. The valve grooves 50, 51, 52, and 53, are so arranged that when the roller 48 of one of the valve levers 46 passes through the complete cycle of the said grooves, the valve will have been turned into 75 position to open the inlet during the charging stroke, close the inlet during the compression and explosion strokes, and close the inlet and open the exhaust port during the scavenging stroke, thus securing the normal 80 valve operation of a four-cycle engine having only one inlet port to the cylinder.

85 Referring to Fig. 5 the travel of each of the rollers 48 in the cam grooves is as follows: The cylinder block is rotated clockwise with respect to the cam face as illustrated in Fig. 5. Supposing a roller of one of the valves is just entering the cam groove 50 at the top of that groove as illustrated in Fig. 5, the cylinder, the valve of which is being considered, will be just commencing its charging stroke,—that is, the valve will be in the position illustrated in the lower corner of Fig. 4, connecting the cylinder to the intake manifold 30, and permitting a 90 charge of fuel to be drawn into the cylinder during the outward travel of a piston therein. After approximately one-half the revolution, the valve roller will have passed through the groove 50 and will have come 95 to the transition portion 54, which carries the roller outward, thus turning the valve to a new position, as the roller passes into the cam groove 52. In passing through the transition portion 54, the valve is turned 100 from the position illustrated at the bottom of Fig. 4 to the position illustrated at the top of that figure, closing the inlet and outlet ports, and trapping the explosive charge 105 in the cylinder. The return stroke of the piston, which occurs while the valve roller is passing around through the cam groove 52, compresses the explosive charge, and then while the roller is going on around through the cam groove 51, which is at the same 110 distance from the center of the cam member, the charge in the cylinder is exploded, and the working stroke takes place while the roller is in the cam groove 51. At the end of this cam groove the roller enters the transition groove 56, which carries it outward again from groove 51 to groove 53, the valve being turned by this transition portion from closed position to the position 115 shown at the right of Fig. 4. This opens the explosive chamber into the exhaust passage 28, and while the roller passes through the cam groove 53 the cylinder is scavenged.

120 A pair of guides 60 and 61 are pivotally mounted on the inner face of the cam mem-

ber, the guide 60 extending across the end of the cam groove 53. The guide 60 is rigidly mounted on a pin 62, which extends through the cam member, and has rigidly 5 mounted on the exterior thereof a crank arm 63, which is connected by a link 64 to a crank arm 65, which in turn is rigidly mounted on the exterior end of a pin 66, which extends to the inner face of the cam 10 member and has fixed thereon the guide member 61.

This arrangement provides for returning the valve roller after it has completed its passage through the cam groove 53, to the 15 beginning of the cycle, that is to the cam groove 50. This transition is caused by the fact that when a valve roller passing around the groove 53 strikes the upper side of guide 60, and also the bounding wall 67 of the 20 outer wall of the cam member, the guide 63 is driven downward, and this through the crank arms 63 and 65, and the link 64 throws the guide 61 upward until it contacts with the outer wall 67, and thus guides the 25 roller downward into the groove 50. Thereafter the cycle is completed as above outlined.

The ignition system for this engine is illustrated in Figs. 7 and 8. A suitable magneto 70 is mounted on the end of the engine shaft 400, and driven thereby. This magneto generates a current which is led by means of connecting post 71, wire 72, connecting post 73, and brush 74, to a rotary 30 contact member 75, which is mounted upon and driven by the extension of shaft 4 which also drives the magneto. Three contact 35 members 76, 77, and 78 are mounted on the periphery of the rotary member 75 and engage the end of the brush 74 consecutively, as will be obvious. The three contact members 76, 77 and 78 are connected by wires 79, 80 and 81, respectively, to the spark 40 plugs. One end of each wire is attached to 45 its respective contact plate, and they extend through the bore in shaft 400, and are led out to spark plugs 82^a, 82^b, and 82^c, which are mounted in the cylinders 1, 2, and 3, respectively in the ordinary manner. It 50 will be understood that the brush 74 makes its contact with the members 76, 77, and 78 at the proper time to furnish a connection from the magneto to the proper spark plug.

The lubrication of the engine is effected 55 through an arrangement which is diagrammatically illustrated in Figs. 2 and 3.

The gear box 15, which is in effect a closed casing, enclosing the gears 16, 17 and 18, merely rides loosely upon the shafts 10 and 60 400. By means of a port controlled by a tap 90, this gear box is partially or wholly filled with oil. A port 91 leads out of the side of the gear box, at a point near where the gears 17 and 18 mesh. This port is surrounded by a small cut out portion 92, in

the thickened wall of the gear case, and the rotating gears act as a pump to force the oil into this space or chamber 92, and produce pressure therein, which forces oil out the port 91, and through the upward passage 70 93 into the passage 94 drilled in the main shaft 10, down the passage 95 drilled in the spider arms 9, through the passage 96 drilled in the pin 20 to which the connecting rod 7 is attached. The passage 96 connects with the passage 97 drilled through the connecting rod 7, which extends to and connects with a passage 98 bored in the piston pin 6 of the piston 4. This passage 98 passes outward and opens into the circular groove 5 which extends around the piston, and the oil is forced around that groove, and back into passage 100, which connects with passage 101 drilled in the connecting rod 7, thence into the return passage 102 drilled in the member 20, thence up through the return passage 103 through the spider arm 9, thence through passage 104 drilled in the main shaft 10, which opens out by port 105 into the gear case 15, all as diagrammatically illustrated in Fig. 2.

By this means a forced circulation of oil lubricates the bearing formed between the connecting rod 7 and the pin member 20, also lubricates the piston pin 6 at its bearing with the piston 4, and also lubricates the piston in its bearing with the interior of the engine cylinder.

The other bearings may be lubricated by any desired manner, not necessary to illustrate.

I claim:

1. A rotary engine comprising a rotatable member carrying a plurality of rigidly connected cylinders tangentially mounted in relation to said rotatable member, a fly-wheel connected to the pistons of said cylinders, a shaft fixed to the rotatable cylinder member, a second shaft rigidly fixed to the fly-wheel at the center thereof, a chain of gears connecting the two shafts together so as to cause them to turn in the same direction at the same speed.

2. A rotary internal combustion engine comprising a rotary shaft, a fly-wheel fixed thereon, a gear fixed on the shaft, a second shaft eccentrically mounted with reference to the first shaft, a block of cylinders mounted upon the said second shaft, said cylinders being mounted in tangential relation to said shaft, pistons in said cylinders, connections from said pistons to the periphery of the said fly-wheel, a gear fixed upon the second shaft, and an intermediate gear connecting the gears upon the first and second shafts whereby to rotate them in the same direction at the same speed.

3. A rotary engine comprising an engine block having a plurality of cylinders tangentially arranged with respect to the axis

of the block, means to supply to and ignite fuel in the said cylinders, pistons in said cylinders, a fly-wheel operatively connected to said pistons, a shaft carrying said fly-wheel, a shaft carrying said engine block, gears on said shafts, and an intermediate member connecting said shaft gears whereby to rotate the two shafts synchronously at the same speed.

10 4. A rotary engine comprising a block of cylinders mounted on a hollow shaft in tangential relation thereto, connections from the pistons of said engine unit to the periphery of a fly-wheel surrounding said engine unit, and connections between the shafts of the fly-wheel and the shaft of the engine, whereby the engine unit is caused to follow the fly-wheel as it is driven by the engine.

15 5. A rotary engine comprising a shaft, a

fly-wheel fixed thereon, a second shaft 20 mounted parallel to the fly-wheel shaft and eccentric thereto, gears on the two shafts and an intermediate connecting gear, all the gears being of the same size, an engine block fixed on the second shaft, said engine block 25 comprising a plurality of cylinders mounted in tangential relation to their carrying shaft and having pistons connected to the periphery of said fly-wheel, the cylinders of the said engine unit being arranged to receive 30 an explosion at the point where they are nearest to the periphery of the fly-wheel, and the gearing between the two shafts being arranged to cause the engine unit to follow the fly-wheel at the same rate of revolution. 35

In testimony whereof, I have hereunto set my hand.

HARRY D. WILLIAMS.
